TUNING ASSEMBLY

Merlin Petroff, Lake Bluff, Ill., assignor to
Stewart-Warner Corporation, Chicago, Ill., a
corporation of Virginia

Application September 3, 1948, Serial No. 47,573

5 Claims. (Cl. 171—242)

1

The present invention relates generally to high frequency inductance tuning devices and more particularly to a new and improved tuning assembly utilizing the inherent qualities of the inductometer circuit.

One of the principal objects of the invention is to provide a tuning device of simple design and low cost construction.

Another object is to provide a tuning device which may be quickly and easily adjusted and which is provided with a minimum of moving parts.

A further object is to provide a tuner having little loss due to stray magnetic fields and of substantially fixed low capacity.

Further objects and advantages will become apparent from the ensuing description of one embodiment of the invention.

In the drawings:

Fig. 1 is an isometric view of the complete tuning assembly unit;

Fig. 2 is a vertical sectional view of the unit taken on the line 2—2 of Fig. 3;

Fig. 3 is a vertical sectional view taken on line 3—3 of Fig. 2;

Fig. 4 is a fragmentary sectional view showing the rotating element of the tuning assembly taken on the line 4—4 of Fig. 3;

Fig. 5 is a plan view of the contactor shown applied to a section of the rotating element;

Fig. 6 is an elevational view of the contactor shown applied to a section of the rotating element;

Fig. 7 is a schematic representation of the electrical connection of the coils of the tuning assembly; and

Fig. 8 is a schematic wiring diagram illustrating a modified form of coupling.

In this tuning assembly the basic elements are shown in Fig. 1 as a rotating disk 10, a stationary plate 12, a bail 14 used to rotate the disk 10, and a contact 16. The contact 16 is more clearly shown in Figs. 5 and 6.

The disk 10 is attached securely to the rotatable bail 14 by small flaps 18 stamped from the bail 14 and secured by rivets to the disk 10 as is clearly shown in Figs. 2, 3 and 4. The disk 10 is circular in shape and made of a suitable type of nonconducting plastic, such as polystyrene. On one side of the disk 10 is a half turn 50 of an inductance coil 20 which is either embossed, printed or electroplated on the disk 10 and consists of a conductive material such as silver. One end of the coil 20 is electrically connected to the rotating bail 14 at 23 and the other 55

2

end terminates at a conducting surface 21 as is clearly shown in Fig. 4. Over this surface 21 is mounted the contactor 16 as shown in Fig. 6. The contactor 16 has arms 22 which extend through suitable slots in the disk 10 and are bent toward each other to bring the contact piece 24 into electrical connection with the contact surface 21 on the disk 10.

The contact 16 has mounted on it a rivet 26 formed of suitable contact material such as silver and is in contact with a contact surface 25 on the stationary plate 12 similar to the contact surface 21 on the disk 10. This contact surface 25 is at one end of a half turn of an inductance coil 28 (Fig. 2) which is of the same type as coil 20 and which terminates in a soldering lug 30 for connection to the leads of a tuning circuit. The plate 12 is formed of a polystyrene-like material and on its other side is printed, or otherwise formed, a coil 32 as shown in Fig. 2. This coil 32 is positioned in axial alignment with the coil 28 and is almost a complete loop. The two ends of this coil are terminated by lugs 34 and 36 which serve to connect this coil to an electrical network. Rods 38 and 40 of nonconductive material are used to support the plate 12 in its stationary position between end supports 42 and 44.

The electrically conductive end supports 42, 44 30 are about the same shape as the stationary plates 12. Support 44 has mounted in it a pin 46 (Fig. 3). The pin 46 is securely attached to the bail 14 and is rotatable in a bushing 48 mounted in the support 44. A washer 50 keeps the bail 14 away from the support 44.

The movable bail 14 carrying the disks 10 is rotated by a nonconductive tuning shaft 52 which rotates in the support 42 and is rigidly fixed to the bail 14. The shaft 52 extends only through the support 42 and is used to rotate the bail 14 and thereby change the position of the disks 10. Due to the construction of the support 42 the arm 14 can be rotated only in a 180 degree arc. The conductive bail 14 is electrically connected to the conductive grounded support 42 by a conductive pigtail 54.

There can be as many groups of the combination of a disk 10 and a plate 12 as is needed for the circuit requirements, and in Fig. 1 two such combinations are shown. As indicated schematically in Fig. 7 the electrical circuit for one such combination would be from lug 30 through the coil 28 to the contact 26 in contactor 16, from the contact surface 24 to the contact surface 21, through the coil 20 to the

rotating bail 14, from the rotating bail 14 to the pigtail 54 and to ground through the support 42. Inductively coupled to the series combination of the coil 28 and the coil 20 is the stationary coil 32. All of these coils are in close proximity to one another so that most of the flux in any one coil will link the other two. Thus, a close coupling will be effected, but not so close as to cause two resonant peaks in the rotating coils when they are connected in a 10 tank circuit.

A typical operation of the tuning assembly would be to use the stationary coil 32 as an 15 relatively rotating coils 28 and 20 would be the secondary of the input transformer, of which coil 32 is the primary, and would be connected to a capacitance thereby forming a tuned tank 20 circuit. In the position of the members as shown the maximum amount of flux from coil 24 32 would link the secondary coils and the greatest inductance will be created in these coils. As 25 rotation in either direction is caused the inductance will decrease due to the fact that less lines of flux can link the coils and a greater self-inductance is set up in the coils to oppose the induced inductance.

Coupling to the variable inductance may also be accomplished in the manner shown in Fig. 8, 30 wherein a conductor 46 leading to the next stage is connected to a fixed tap 43 on coil 28 through a small series condenser 44, thus making the use of the coil 32 unnecessary.

While I have shown and described a preferred embodiment of my invention, it will be 35 apparent that numerous variations and modifications thereof may be made without departing from the underlying principles of the invention. I therefore desire, by the following claims, to include within the scope of the invention all such variations and modifications by which substantially the results of my invention may be obtained through the use of substantially the same or equivalent means.

I claim.

1. A tuning assembly, comprising a stationary plate, a rotating plate, a layer of conducting material on one side of the stationary plate in the form of a single turn of a coil, a layer of conducting material on the other side of the stationary plate in the form of a one-half turn of a coil, a layer of conducting material in the form of a one-half turn of a coil on the rotating plate, the rotating plate being arranged parallel to and closely adjacent the stationary plate, an electrical contact between one end of the one-half turn coil on the rotating plate and one end of the one-half turn coil on the stationary plate, a movable bail connected to the rotating plate, means forming an electrical connection between the other end of the one-half turn coil and the bail, and means for selectively positioning the movable bail with respect to the stationary plate.

2. A tuning assembly comprising a stationary plate, a rotating plate, a layer of conducting material on one side of the stationary plate in the form of a single turn of a coil, a layer of conducting material on the other side of the stationary plate in the form of a one-half turn of a coil, a layer of conducting material in the form of a one-half turn of a coil on the rotating plate, the rotating plate being arranged parallel to and closely adjacent to the stationary plate,

means electrically connecting one end of the one-half turn coil on the rotating plate and one end of the one-half turn coil on the stationary plate, a movable bail connected to the rotating plate, means forming an electrical connection between the other end of the one-half turn coil and the bail, and means for selectively positioning the movable bail with respect to the stationary plate.

3. A tuning assembly, comprising a stationary plate, a rotating plate, a layer of conducting material on one side of the stationary plate in the form of a single turn of a coil, a layer of conducting material on the other side of the stationary plate in the form of a one-half turn of a coil, a layer of conducting material in the form of a one-half turn of a coil on the rotating plate, the rotating plate being arranged parallel to and closely adjacent the stationary plate, a movable electrical contact between one end of the one-half turn coil on the rotating plate and one end of the one-half turn coil on the stationary plate, a movable bail connected to the rotating plate, means grounding the other end of the movable one-half turn coil, and means for selectively positioning the movable bail with respect to the stationary plate.

4. A tuning assembly, comprising a stationary plate, a rotating plate, a layer of conducting material on one side of the stationary plate in the form of a single turn of a coil, a layer of conducting material on the other side of the stationary plate in the form of a one-half turn of a coil, a layer of conducting material in the form of a one-half turn of a coil on the rotating plate, the rotating plate being arranged parallel to and closely adjacent the stationary plate, a movable electrical contact between one end of the one-half turn coil on the rotating plate and one end of the one-half turn coil on the stationary plate, and means for variably positioning the rotating plate with respect to the stationary plate.

5. A tuning assembly, comprising a plurality of pairs of plates, each pair consisting of a stationary plate, a rotating plate, a layer of conducting material on one side of the stationary plate in the form of a single turn of a coil, a layer of conducting material on the other side of the stationary plate in the form of a one-half turn of a coil, a layer of conducting material in the form of a one-half turn of a coil on the rotating plate, the rotating plate being arranged parallel to and closely adjacent the stationary plate, means electrically connecting one end of the one-half turn coil on the rotating plate and one end of the one-half turn coil on the stationary plate, a movable member connected to the rotating plate, means forming an electrical connection between the other end of the one-half turn coil and the movable member, and means for selectively positioning the movable member with respect to the stationary plate.
